CIRCUIT BREAKERS

Paul M. Christensen, West Orange, and Dominik Wiktor and John Bryan, Newark, N. J., assignors to Federal Pacific Electric Company, a corporation of Delaware

Application November 2, 1955, Serial No. 544,465

19 Claims. (Cl. 200—116)

The present invention relates to circuit breakers and in particular to small molded-case breakers of the type employed in lighting distribution panelboards and in domestic circuit protection in lieu of fuses.

An object of the invention is to provide a small circuit breaker of novel construction having quick-break characteristics when manually operated for opening the contacts, even if the person operating the handle should arrest the handle part way toward open position. A further object of the invention is the provision of such a novel circuit breaker having quick-break characteristics without resort to an over-center spring.

Small circuit breakers have been widely used in which a moving contact is operated from open circuit to closed circuit condition, and reversely, in which an over-center spring is employed for biasing the moving contact both in the closed and in the open direction, depending on the configuration of the operating mechanism. Over-center springs have the important disadvantage of exerting zero force at the moment that they pass dead center. At such time, there is the zero contact pressure and there is also zero tendency of the spring to drive the contacts apart, while this condition theoretically exists at only an infinitesimal point in the opening stroke of the operating handle, as a practical matter friction enters the picture so that an appreciable portion of the operating stroke may be found to give weak and uncertain contact pressure. If the handle were deliberately operated in a decisive stroke then there would be no problem. However, there is the possibility that one might deliberately retard the handle, or operate it very gradually; and the specifications of some users concerning circuit breakers require quick closing and quick opening despite all possible deliberate attempts to control the operation of the handle.

The present invention is concerned with a type of circuit breaker in which a spring is arranged to bias the contacts away from each other at all times, even when the contacts are closed, in contrast to over-center spring mechanisms. When the breaker is closed, a locking mechanism holds the contacts closed, against this spring bias. When the locking mechanism has been released manually, the spring is fully effective at the very start of the opening stroke to drive the contacts apart. Such a circuit breaker is improved, according to the present invention, to avoid all possibility of hindering the opening by mis-operation of the handle.

A further object of the invention is to provide a novel small circuit breaker with quick-make and quick-break characteristics when operated manually without resort to over-center spring mechanisms for operating the movable contact. It is understood that the circuit breaker should also have quick-break characteristics when automatically tripped by an overload.

The foregoing objects are achieved in the novel illustrative circuit breaker described below in detail, in which certain additional features of novelty and advantages

2

will be apparent. In the detailed description, reference is made to the accompanying drawings, wherein:

Fig. 1 is a lateral view of a circuit breaker embodying the invention with portions of the enclosure being broken away to reveal the internal mechanism;

Fig. 2 is a similar view with the handle in a shifted position compared to Fig. 1, and with certain parts shown in dotted lines to represent a still further operating position.

10 Fig. 3 is a fragmentary cross-section of a portion of the novel circuit breaker along the line 3—3 in Fig. 1.

Fig. 4 is a fragmentary cross-section of the novel circuit breaker along the line 4—4 of Fig. 3.

15 Fig. 5 is an enlarged fragmentary cross-section of a portion of the novel apparatus along the line 5—5 in Fig. 1.

Fig. 6 is a perspective of the handle of the circuit breaker in Figs. 1, 2 and 5; and

20 Fig. 7 is a perspective of the element in Fig. 1 that cooperates with the handle shown in Fig. 6.

Referring now to the drawings, there is shown a pair of housing members 10 and 12 of molded insulation which support and enclose the operating mechanism of the novel circuit breaker. This includes a fixed contact 25 14 on an external terminal member 16; movable contact 18 on contact carrier 20, having a coil-spring pivot 22, contact 18 being shown to the left of pivot 22; an actuator 24 having a pivot 26 in contact carrier 20 to the right of coil-spring pivot 22; a current-responsive bimetal 28 united at its left end to contact carrier 20 and at its right end being in latching engagement with actuator 24; and a second terminal 30 connected by flexible braid 32 to the current-responsive bimetal 28 near the latch end of this bimetal. A bimetal 24a for compensating 30 for ambient temperature variations is as shown which may be regarded as a part of actuator 24. The current path through the circuit breaker thus far described extends from terminal 16, through fixed and movable contacts 14 and 18, through contact carrier 20, bimetal 28 and flexible braid 32 to terminal 30 which is designed to stab into a live bus receptacle. Pivot 26 embodies insulation (not shown) to interrupt any possible current path from bimetal 28 through actuator 24 to contact carrier 20.

35 40 45 The contact carrier is shown in its "closed" position with movable contact 18 bearing against fixed contact 14. The mechanism for operating contact carrier 20 between its closed and open positions is as follows:

50 A link 34 which is a U-shaped piece of stiff wire has the sides of the U disposed perpendicular to the view so as to form two pivots. One of these has a bearing in the upper end of the actuator 24 and the other has a bearing in a member 36 (Figs. 1, 2, 5 and 7). Handle 55 38, pivoted on an integral stub shaft 10a (Fig. 5), operates member 36 to close the circuit breaker when shifted to the extreme left in Fig. 1, and this handle opens the circuit breaker when it is shifted to the right. The cooperation of members 36 and 38 will be discussed in detail below. In the configuration shown, member 36 and element 34 constitute a pair of toggle members which are slightly over-center. The extent of over-centering is limited by engagement of member 36 against an integral stop 40 formed in insulating housing member 12.

60 65 70 A similar stop portion is formed in housing portion 10 which is broken away from the view in Fig. 1. The pivotal connection between members 34 and 36 (Fig. 1) is above the center line extending from the pivotal axis of member 36 to the pivot axis of member 34 in the actuator 24. In this condition the toggle is said to be locked.

Pivot spring 22 which appears in Figs. 1 and 2 and is

shown somewhat enlarged in Figs. 3 and 4, serves a number of purposes. In the form of circuit breaker illustrated, all of the elements between the toggle member 36 and the fixed contact 14, including elements 34, 24 and 20, are rigid in this illustrative circuit breaker. When toggle 34, 36 is in the position shown, a degree of resilience is introduced in the mechanism which enables contact 18 to bear against contact 14, despite reasonable variations in the parts dimensions in volume manufacture of such circuit breakers. In this function, spring 22 serves as a pivot and it also functions with upward spring bias to swing contact carrier 20 counterclockwise about pivot 26 to develop contact pressure when the toggle 36, 34 is locked and pivot 26 is fixed. A compression spring 44 is shown that acts between the contact carrier 20 and member 36, in the direction to open the contacts and to shift member 36 and handle 38 to the "off" or reset position. The force of spring pivot 22 to bias the contacts closed when the toggle is locked is considerably greater than the reverse action of spring 44. Nonetheless spring 44 biases the contact arm 20 in the opening direction to be instantly effective to open the contacts when the toggle is released.

The linkage including toggle 34, 36 and actuator 24 is effective to operate the contact carrier 20 into closed configuration only when the lower tip of actuator 24 is arrested by the end of bimetal 28. This bimetal may be described as a current-responsive latch which arrests actuator 24. The handle 38 and toggle 34, 36 operates through actuator 24 to operate carrier 20 for closing the circuit breaker when the actuator is latched. When current passes through bimetal 28 it heats and curves downward. It passes out of latching engagement with actuator 24 when a critical temperature is exceeded corresponding to the current rating of the circuit breaker.

A rigid soft iron bar 42 is united to contact carrier 20 at the same point where bimetal 28 is anchored. In the event of a very sudden overload current through bimetal 28, the resulting flux developed by that current about the bimetal links bar 42. A downward deflecting force is developed, flexing bimetal 28 toward bar 42 and out of latching engagement with actuator 24.

When current-responsive latch 28 releases actuator 24, either because of thermal effect or magnetic effect, actuator 24 swings clockwise about its pivot 26. Compression spring 44 then operates to drive contact carrier 20 counterclockwise. Toggle 24, 26 is not effective to prevent such motion, when actuator 24 is released. Compression spring 44 separates the contacts at high velocity when current-responsive latch 28 releases actuator 24. There is no lack of spring pressure to open the contacts following the instant that actuator 24 is released, no "dead-center" condition such as is involved in over-center spring mechanisms.

Apart from the snap action found in opening the contacts after release due to overload, the present circuit breaker operates with snap action both in opening and in closing the contacts in response to manual operation of handle 38.

Handle 38 is operated from the extreme right position (not shown) to the extreme left position shown in order to close the circuit breaker. When the handle is operated in this fashion toggle member 36 is operated counterclockwise and toggle member 34 applies thrust to actuator 24 in order to actuate contact carrier 20 in the clockwise closing direction. A V shaped member 46 is rockably mounted on contact carrier 20 and, during contact-closing travel of the contact carrier, member 46 is biased by spring 44 so that the left-hand arm of member 46 travels along a cam surface 48 formed in the insulating housing parts 10 and 12. The upper end of the cam surface 48 has a shoulder which arrests member 46 as well as contact carrier 20 at a point prior to engagement of contact 18 against contact 14. Thereafter further operation of handle 38 in the closing direction drives toggle member 34 and actuator 24 without corresponding travel of con-

tact 18. During this further travel, spring pivot 22 becomes stressed so as to assume approximately the position in Fig. 3. This stress shifts contact carrier 20 downward and somewhat to the right in Fig. 1, and operation of member 36 counterclockwise also shifts spring 44 against the righthand arm of member 46. The result of both these actions is to shift member 46 out of engagement with the shoulder portion of cam 48. Thereafter pivot spring 22 drives contact 18 against contact 14 with a snap action. At this phase of the operation toggle 34, 36 has been shifted over-center and is nearly against stop 40. Compression spring 44 is ineffectual to separate the contacts at this stage. Snap-closing of the contacts cannot be avoided even by deliberate, slow operation of the handle 38 in the closing direction.

As seen in Figs. 5 and 6, handle 38 is supported on a bearing 19a formed as a projection extending from housing wall 10. Arm 38a extends out of the casing 10, 12 as an integral operating lever. Annular bearing portion 20 38b is of limited axial thickness, the space between members 12 and 10 being filled by a flange extension 38c of the handle 38. The arcuate extent of flange 38c about bearing 19a is here shown as about 10° less than that between shoulders 36b and 36c of toggle member 36 (Fig. 25 7). This difference in arcuate extent of the flange 38c and the space between the shoulders of toggle member 36 enables handle 38 to pivot with limited lost motion without affecting toggle member 36. Handle 38 is held against shifting from the position in Fig. 1 to that in Fig. 2 by a leaf-spring detent 50 received in an appropriate recess in member 12, a similar recess also being formed in housing member 10. Flange 38c and portion 38b close off the opening in housing 10, 12 required for the operating stroke of handle 38a, preventing access to the mechanism and minimizing the number of crevices into which operation-hindering dirt might collect.

Handle 38 is operated clockwise in the opening direction without affecting member 36, until handle 38 reaches the position represented by the solid lines in Fig. 2. In this phase, flange 38c leaves shoulder 36b and reaches shoulder 36c, a lost-motion operation. Further shifting of handle 38 counterclockwise into the dotted line position causes toggle 34, 36 to shift overcenter into the dotted line configuration shown in Fig. 2. Manual retention of handle 38 in the dotted line position can no longer restrain contact carrier 20, for thereafter spring 44 drives the contact carrier into open position, with portion 52 of contact carrier 20 against stop 54 formed on the inside of housing walls 10 and 12. With the handle restrained, toggle member 36 moves clockwise and reversely takes up the space between flange 36c and shoulder 36b. If handle 38 is released in any stage short of full "off" position, spring 44 completes the reset of the handle, thereby forcing the handle into reset position in condition to close the breaker when desired. During the manual opening stroke actuator 24 remains opposite the end of bimetal 28.

Spring 44 is effective to return actuator 24 from the clockwise position assumed after release of the circuit breaker by current overload and into normal position ready for reclosing, by virtue of a rounded right-hand lower end of bimetal 24a, suitably polished, that slides over the top surface of bimetal 28 during such reset operation of the bimetal.

In the event that handle 38 should be mechanically locked in "on" position following automatic tripping in response to an overload, member 24 remains in its tripped position (clockwise relative to that illustrated) while the bimetal cools. When the handle is thereafter operated to "off" position, it takes up the lost motion and then can drive the linkage 36, 34, 24 into reset configuration, with the tip of the bimetal 24a opposite the end of latch member 28. Spring 44 naturally tends to effect this reset; but in case friction of actuator 24 in moving across the top surface of member 28 should prove too great for this action, positive operation of the handle will effect

reset. Also, in case this invention is applied to a circuit breaker in which latch 28 is pivoted rather than fixed at its left end, this specialized condition of frictionally inhibited reset after automatic trip does not occur.

The foregoing disclosure represents the presently preferred embodiment of the invention, as applied to a known form of circuit breaker, but it should not be inferred the invention is limited to this specific form of circuit breaker. Other forms omitting bimetal 24a may be desired; resilience may be introduced using a rigid pivot in place of spring pivot 22; and snap-closing is not dependent on the particular form of mechanism shown. Therefore it is appropriate that the invention should be construed broadly in accordance with its full spirit and scope.

What is claimed is:

1. A circuit breaker including an insulating enclosure, a fixed contact mounted therein, a movable contact carrier bearing a movable contact, a current-responsive latch carried by said contact carrier, an actuator pivoted to said contact carrier and engageable with said current-responsive latch, said actuator when engaged with said latch being operable thereafter to actuate said contact carrier for closing the contacts, a toggle including a first toggle member pivoted to said actuator and a second toggle member pivoted to said insulating housing and pivotally connected to said first toggle member, a compression spring having one end acting against said contact carrier and having its opposite end acting against said second toggle member and being continuously effective to bias said contact carrier and said second toggle member toward their respective circuit-breaker-open positions, and said toggle being effective to operate said actuator and thereby to operate said contact carrier to circuit-breaker-closed position against the bias of said spring, said toggle shifting over center into locking position when the circuit breaker is closed, a handle for said second toggle member having a portion thereof projecting out of the enclosure through an aperture therein and being operable to shift said second toggle member over-center in one direction to close the circuit breaker and said handle being reversely operable to release the toggle, there being a lost motion connection between said handle and said second toggle member whereby the toggle, when shifted from circuit-breaker-closed configuration and over-center moves out of the locking position and enables the compression spring to drive a contact carrier into circuit-breaker-open position despite possible arresting of said handle during its circuit breaker opening stroke, said spring being effective when the handle is released during an opening stroke to operate said toggle and said handle into extreme "open" position, in condition for a reclosing operation of the circuit breaker.

2. A circuit breaker in accordance with claim 1 wherein in said handle embodies an arcuate flange concealing said second toggle member in all operative positions of the portion of the handle projecting through said aperture.

3. A circuit breaker in accordance with claim 1 wherein in said handle and said second toggle member have coaxial pivots, said handle embodying an arcuate flange closing off the aperture in the housing in all positions of the handle, said flange having a concave bearing surface and said second toggle member having a complementary arcuate convex bearing surface with shoulders at the arcuate extremities thereof, the arcuate extremities of said flange coacting with said shoulders for operating the toggle, the arcuate extent of said flange being appreciably less than the arcuate separation between said shoulders and thereby establishing said lost motion connection between said handle and said second toggle member.

4. A circuit breaker including an insulating housing having an aperture therein and containing the operative mechanism thereof, said mechanism including a fixed contact, a movable contact carrier bearing a movable contact, a handle projecting from said aperture and operatively connected to said movable contact carrier to

drive the movable contact from open to closed position, said mechanism including yielding spring means and a detent arresting the closing motion of the movable contact member during closing operation of the handle, said yielding spring means producing snap closing of the contacts after release of the detent, means locking the contacts closed, spring means at all times biasing the contacts toward open position; and a lost motion connection between said handle and said contact carrier effective to release the locking means and thereby enable said biasing spring to open the contacts despite possible arresting of the handle part way toward open position after release of said locking means.

5. A circuit breaker including an insulating housing having an aperture therein and containing the operative mechanism thereof, said mechanism including a fixed contact, a movable contact carrier bearing a movable contact, a handle projecting from said aperture and operatively connected to said movable contact carrier to drive the movable contact from open to closed position, means for locking the contacts closed, spring means at all times biasing the contacts toward open position, said spring means also being arranged to drive the handle in the contact-opening direction upon release of the locking means, and a lost motion connection between said handle and said locking means providing for limited idle operation of said handle in relation to the locking means followed by release of the locking means by the handle upon further operation thereof in the releasing direction, and said spring being effective thereafter to snap-open the contacts free of inhibiting action by said handle.

6. A circuit breaker having an insulated housing formed with an aperture and containing the operative circuit breaker mechanism, a pivoted handle having a flange closing said aperture and having a manually engageable portion projecting externally of the housing through said aperture, a member pivoted in the housing coaxially with said handle and having arcuately separated shoulders disposed for coaction with the arcuate extremities of the handle flange, said extremities being separated by a smaller angle than the separation between said shoulders whereby to establish a limited lost motion connection between said handle and said member, a fixed contact in said housing, a movable contact cooperable therewith and movable between open position spaced from said fixed contact and closed position against said contact, a spring operative at all times to bias said movable contact toward open position and to bias said shouldered member toward circuit-breaker-open position, a linkage operated by said member to drive said movable contact toward circuit-breaker-closed position against said spring bias and including means locking the circuit breaker closed, said handle being effective to shift said shouldered member to release the locking means and said biasing spring being thereafter effective to open the contacts, said handle being ineffective to arrest the opening of the contacts after release of the locking means by virtue of the lost motion between said handle and said cooperating member, said biasing spring being effective upon release of the handle to shift the handle into circuit-breaker-open position.

7. A circuit breaker having an insulating enclosure formed with an aperture, a pivoted handle extending from said aperture and having an arcuate portion closing the said aperture in all operative positions of the handle and having an operating portion projecting externally of the housing through said aperture, a pivoted member co-operating with said handle and formed with spaced shoulders, said handle also having spaced portions coacting with said shoulders, the spacing between said handle portions and the spacing between said shoulders being different and forming a lost motion connection, a fixed contact in said enclosure and a contact carrier bearing a movable contact coacting with said fixed contact, a biasing spring arranged to provide contact opening bias in all

positions of the contact carrier, a linkage operated by said handle and including means for locking said contacts when closed by handle operation, said linkage including a current-responsive latch and an actuator cooperating with said latch, said latch being arranged upon current overload through the circuit breaker to release said linkage and enable said biasing spring to open the contacts, said handle also being effective to release said locking means, thereby to enable said biasing spring to open said contacts, said lost motion connection preventing said handle from interfering even if held in locking-means-releasing position.

8. A circuit breaker including an insulating enclosure having an aperture therein, separable contacts in said enclosure, a handle extending from the interior of the enclosure through said aperture, said handle being operable in reverse directions to open and to close the circuit breaker, a linkage connecting said handle to operate one of said contacts, said linkage including a member in the enclosure cooperating with said handle through a lost motion connection therewith, a spring biasing the contact carrier toward open circuit position in all configurations of said linkage and said linkage having locking means holding the contact carrier in closed position despite said biasing spring, said locking means being releasable by said handle, said linkage further including a current-responsive latch and an actuator cooperative with said latch effective to release said linkage for circuit breaker opening operation in response to overload current, said spring also being effective to open said contacts when said handle is operated toward circuit breaker opening position and after release of said locking means despite possible interruption of handle operation in locking means releasing position.

9. A circuit breaker in accordance with claim 8 wherein said operative linkage includes yielding spring means interposed between said cooperating member and said movable contact carrier, detent means arresting said contact carrier during closing operation of said handle, said arresting means being arranged to release the contact carrier for snap closing of the contacts under the influence of said yieldable spring means during further contact closing operation of said handle, thereby to cause snap-closing of the contacts as well as snap-opening of the contacts irrespective of gradual operation of the handle in both directions.

10. A circuit breaker including a fixed contact, a movable contact carrier bearing a movable contact and having a supporting pivot, an actuator carried by said contact carrier, a current-responsive latch carried by said contact carrier, said contact carrier and said actuator and said current-responsive latch being held in substantially rigid triangular assembly when said contacts are closed and said actuator being releasable by said latch upon overload, a first toggle member pivoted to said actuator, a second toggle member having a fixed pivot and further having a pivotal connection to said first toggle member, and a spring continuously acting in compression between said second toggle member and said contact carrier in contact-opening direction and in the direction to drive said second toggle member toward normal open-circuit-breaker position, a handle cooperable with said second toggle member and having a lost-motion connection thereto for operating said toggle members in one direction over center into contact-closed position and operable in the reverse direction to shift the toggle from contact-closed position and over center, with the lost-motion connection thereafter being effective to insure operation of the contact carrier into open position despite the possibility of said handle being arrested.

11. A circuit breaker including a first contact, a movable contact carrier bearing a second contact engageable with the first contact, a current-responsive latch operable to maintain said contacts closed and to release the con-

tact carrier for opening said contacts in response to a current overload, and actuating mechanism for said movable contact carrier including a first toggle member operatively connected to said movable contact carrier, a second toggle member having a first pivot and having a pivotal connection to said first toggle member spaced from said first pivot, said toggle members being movable over center in reverse directions to close and open said contacts, a spring continuously biasing said contact carrier in the circuit-opening direction and continuously biasing said second toggle member toward open-circuit-breaker position, an operating member having a lost-motion connection to said second toggle member and effective to operate the toggle from open contact position over center to closed contact position, said operating member being operative reversely to operate the toggle from closed contact position and over center, said biasing spring being then operative to open the contacts, the lost-motion connection being effective to prevent the contacts from being retarded by arresting the manual operator, said actuating mechanism for the moving contact carrier including a detent for arresting the movable contact carrier with the contacts separated during closing operation of said operating member and a yieldable spring enabling continued operation of the manual operator in the closing direction after the contact carrier is arrested by the detent, whereby release of the detent will allow said yieldable spring to close the contacts abruptly, to achieve both snap-opening and snap-closing of the contacts by operation of the manual operator, despite gradual operation thereof.

12. A circuit breaker including a fixed contact, a movable contact carrier bearing a movable contact, an operating mechanism including a manual operator effective to move said movable contact carrier from circuit-breaker-open position to circuit-breaker-closed position and including a snap-closing spring, support means for said mechanism, and means cooperating with said support means and effective during a closing stroke of said manual operator to arrest the advance of the movable contact carrier and thereafter being effective to release the movable contact carrier for abrupt closing of the contacts by said snap-closing spring, a contact-opening spring operatively connected to said contact carrier so as to bias the contact carrier in the contact-opening direction in all phases of circuit-breaker operation, said operating mechanism including means locking the contact carrier in closed position, and a current-responsive overload release for said locking means, said manual operator having a lost-motion connection to said mechanism and being effective to release said locking means for opening of the circuit breaker by said opening spring, said lost motion connection preventing the manual operator from retarding opening of the circuit breaker after said locking means has been released.

13. A circuit breaker including an insulating housing having an aperture therein and containing the operating mechanism thereof, said mechanism including a fixed contact, a movable contact carrier bearing a movable contact, a handle projecting from said aperture and operatively connected to said movable contact carrier to drive the movable contact from open to closed position, said mechanism including yielding spring means and a detent arresting the closing motion of the movable contact member during closing operation of the handle, said yielding spring means producing snap-closing of the contacts after release of the detent, current responsive means and locking means controlled thereby for holding the contacts closed, and a lost-motion connection between said handle and said locking means providing for limited idle operation of said handle in relation to said locking means followed by release of the locking means by the handle when the handle is moved in the releasing direction, and said lost-motion connection accommodating reverse relative idle operation of the locking means when the spring

drives the contacts open free of all possibility of retarding control by the handle.

14. A circuit breaker including an insulating housing having an aperture therein and containing the operating mechanism thereof, said mechanism including a fixed contact, a movable contact carrier bearing a movable contact, a handle projecting from said aperture and operatively connected to said movable contact carrier to drive the movable contact from open to closed position, current responsive means, locking means controlled by said current responsive means for holding the contacts closed, said mechanism including a lost-motion connection having a first part on the handle driving side and having a second part on the driven side of the connection and a spring acting against said second part of said lost-motion connection and effective to bias said handle in the "open" direction when the circuit breaker is open, said spring also acting at all times on said movable contact carrier for biasing the contacts in the opening direction.

15. A circuit breaker having an insulating enclosure formed with an aperture, a pivoted handle extending from said aperture and having an arcuate flange closing said aperture in all operative positions of the handle and said handle having an operating portion projecting externally of the housing through said aperture, an operated member pivoted coaxially with said handle and having a convex curved surface mating with a concave curved surface of said arcuate flange, said operated member having shoulders cooperable with the arcuate extremities of said flange and said shoulders being spaced further apart than said shoulders whereby to afford limited arcuate operation of the handle without enforcing corresponding operation of the operated member, and circuit breaker mechanism contained within said enclosure and including a pair of contacts operable by said operated member for closing and opening of the circuit through the circuit breaker.

16. A circuit breaker in accordance with claim 15 wherein said enclosure includes confronting walls one of which provides a bearing for said handle and the other of which provides a bearing for said operated member, said operated member providing a further bearing support for the handle by virtue of the convex arcuate surface of the operated member and the cooperating concave arcuate surface of said flange.

17. A circuit breaker including an insulating housing having an aperture therein and containing the operative mechanism thereof, said mechanism including a first contact, a movable contact carrier bearing a second contact cooperable with said first contact when the circuit breaker is closed, a current responsive device carried by said movable contact carrier, a member pivoted to said contact carrier and movable into latching engagement with said current responsive device, a pivoted handle for operating said mechanism projecting exteriorly of said housing, a toggle for operating said member into latching engagement with said current responsive device and effective thereafter for driving said contact carrier to close the contacts, said toggle including a first member pivoted coaxially with said handle and a second member interconnecting said first toggle member and said latching member, said handle having a lost-motion connection to said first toggle member, and a spring acting between said contact carrier and said first toggle member and effective to bias the handle in the opening direction

and the contact carrier in the opening direction when the circuit breaker is open and effective to maintain contact opening bias on the contact carrier when the circuit breaker is closed, said lost-motion connection enabling limited idle movement of the handle in the contact opening direction followed by operation of the toggle in the contact releasing direction to enable the spring to open the contacts, and to enable the spring to provide drive for said handle via said first toggle member in the "open" direction of handle operation.

18. A circuit breaker including an insulating housing having an aperture therein and containing operative mechanism thereof, said mechanism including a fixed contact, a movable contact carrier bearing a movable contact, an actuator and overload release means cooperable with each other and carried by said movable contact carrier, a handle projecting from said aperture and operatively connected to said movable contact carrier via said actuator when the latter is in cooperative relation with the overload release means to drive the movable contact from open to closed position, means for locking the contacts closed, spring means at all times biasing the contacts toward open position, and a lost motion connection between said handle and said movable contact carrier and including means to release the locking means, said lost motion connection providing for limited idle operation of said handle in relation to the locking means followed by release of the locking means by the handle upon further operation thereof in the releasing direction, and said spring being effective thereafter to snap-open the contacts free of inhibited action of said handle.

19. A circuit breaker including an insulating housing having an aperture therein and containing the operative mechanism thereof, said mechanism including a fixed contact, a movable contact carrier bearing a movable contact, an actuator and overload release means cooperable with each other and carried by said movable contact carrier, a handle projecting from said aperture and operatively connected to said movable contact carrier via said actuator to drive the movable contact from open to closed position, said mechanism including yielding spring means and a detent arresting the closing motion of the movable contact member during closing operation of the handle, said yielding spring means producing snap closing of the contacts after release of the detent, means locking the contacts closed, spring means at all times biasing the contacts toward open position, and a lost motion connection between said handle and said contact carrier effective to release the locking means and thereby enable said biasing spring to open the contacts despite possible arresting of the handle part way toward open position after release of said locking means.
